UNITED STATES PATENT OFFICE

137,593

DESIGN FOR A DOLL

Tilda V. Fulton, Charlotte, N. C., assignor of one-half to Annie L. Teague, Charlotte, N. C.

Application January 31, 1944, Serial No. 112,388

Term of patent 3½ years

(Cl. D34—4)

To all whom it may concern:

Be it known that I, Tilda V. Fulton, a citizen of the Republic of Czechoslovakia, residing at Charlotte, in the county of Mecklenburg and State of North Carolina, have invented a new, original, and ornamental Design for a DOLL, of which the following is a specification, reference being had to the accompanying drawings, forming a part thereof.

I claim:

The ornamental design for a doll, substantially as shown.

TILDA V. FULTON,
